UNITED STATES PATENT OFFICE.

LOTHAR STOYE, OF CLEVELAND, OHIO.

RAILWAY TIE AND RAIL-SECURING MEANS.

Application filed October 23, 1924. Serial No. 745,317.

To all whom it may concern:

Be it known that I, LOTHAR STOYE, a citizen of the United States, residing at Cleveland, in the county of Cuyahoga and State 5 of Ohio, have invented certain new and useful Improvement in Railway Ties and Rail-Securing Means, of which the following is a specification.

This invention relates to railway ties, particularly ties composed chiefly of reinforced concrete or similar materials.

It has as one of its chief objects the provision of a reinforced concrete railway tie which is characterized as being relatively 15 light as compared with ties of similar composition, and sufficiently strong and resilient to withstand severe service conditions without breakage.

Another object is to construct a concrete 20 tie upon which the rails may directly rest and to which they may be adjustably secured.

A further object is to construct a reinforced concrete railway tie provided with 25 means embedded in the tie and substantially flush with the top surface thereof for securing a rail in direct contact with the top surface of the tie.

A still further object is to provide means 30 insertable in a tie composed of concrete or similar material for adjustably securing a rail thereto.

Other objects will appear and be pointed out in the appended specification.

35 In the drawings attached and forming a part of this specification—

Figure 1 is a perspective view of a tie embodying my invention and assembled with two rails.

40 Figure 2 is a longitudinal section taken on line 2—2 of Fig. 1.

Figures 3 and 4 are, respectively, transverse sectional views taken on lines 3—3 and 4—4 of Fig. 1.

45 Figure 5 is an enlarged, longitudinal, sectional view of the rail securing means assembled with a rail.

Figures 6 and 7 are, respectively, top plan and longitudinal sectional views of a 50 modified form of rail securing means.

The present embodiment of my invention comprises a tie 1 composed of concrete or similar material 2 having a longitudinally extending cavity 3 in the interior thereof and within a metallic reinforcing means 4, preferably wire netting, box shape with

closed ends and with depressions 5 formed in the top thereof adjacent either end of the tie. The reinforcing means or netting, is spaced approximately an equal distance 60 from the top, bottom, sides and ends of the tie 1. In a tie for a standard gauge railroad I have found it satisfactory to space the netting about 1 inch from each face of the tie. The cavity 3 may be formed conveniently 65 by a shell 6 of stiff paper or sheet metal, which is placed in the desired position during the manufacture of the tie.

In the top of the tie 1 are located one or more sets of rail securing means. Each set 70 comprises an insert 8 embedded in the tie and one or more rail clamps 9 secured thereto by securing means 10. The inserts 8 which are preferably composed of metal are elongated members having longitudinal 75 flanges 11 depending divergently from the bottom thereof. Each insert has a recess 12 and a slot 13 enlarged at either end and extending therefrom through the top wall of the insert. When the sides and ends of insert 8 and flanges 11 are inclined substantially as shown they serve as means for locking the insert securely in position in the tie 1. The insert 8 is of such size that it projects into depressions 5 in the reinforcing material 4 but is spaced apart therefrom when its top surface is substantially flush with the top surface of the tie 1. In such position a rail 14 contacts with the top of the member 8 and also rests directly on the 80 top of tie 1. The rail clamps 9 each have an inclined portion to engage with the top surface of the base of a rail 14 and a portion having serrations 15 on its under surface to engage with corresponding serrations 15' extending transversely of insert 8. Any suitable means may be used to hold clamp 9 and insert 8 in assembled position such for example as a headed bolt 10 insertable through 85 the enlarged end 16 of slot 13 to slide in recess 12 with the head of the bolt engaging the top wall of recess 12.

In Figs. 6 and 7 I have shown a slightly modified form of my invention in which 17 designates an insert similar in substantially 100 all respects to insert 8 except that instead of having a clamp 9 on either side of rail 12, one end of the insert is formed with an integral upwardly extending projection 18 formed to engage with the top surface of a 110 rail base. With such an insert only a single clamp 9 is required to hold a rail in as-

sembled position with insert 17, the projection 18 taking the place of the other clamp 9, shown in Fig. 5.

In constructing a tie embodying my invention I provide a mold consisting of bottom and sides corresponding to the top surface and sides and ends of tie 1. Members 8 are placed with the top surface thereof on the bottom of the mold and then the reinforcing material, for example suitably formed wire netting 4, is supported in the mold by suitable wire or sheet metal supports (not shown) and finally a shell 6 is similarly supported within the netting 4. A mixture of sand, cement and water, with or without other suitable materials for making strong concrete, is then brought into the mold and caused to fill completely the mold both within and without the netting 4. It will be understood that with sufficiently fine material having the necessary fluidity this may be easily accomplished since it will readily flow through the netting and into the various angles and corners of the mold without difficulty. After the material has dried or become sufficiently hard to retain its shape the mold may be withdrawn.

The cavity 3 in the tie not only lightens the tie, as compared with other concrete ties, but also appears to affect advantageously the property of the tie to resist severe shocks and seems to confer considerable resiliency upon the concrete structure. Inasmuch as the rail rests directly upon the top surface of the tie, the weight of a car passing over the rail is transmitted to substantially the entire width of the tie and absorbed thereby, the inserts 8 or 17 thus serving merely as rail securing means and not as the main support for the rail. Although the cavity 3 is shown in Fig. 2 as being of substantially the same cross sectional dimensions throughout its length it may be enlarged between the inserts 8, or in other parts, if desired, and the structure still further lightened thereby.

Although I have shown my invention embodied in a single tie for both rails of a railroad it will be understood that a tie embodying my invention may be used with securing means for a single rail and with one rail only.

It will be understood that insert 8 possesses the advantage that a rail may be shifted back and forth on the tie and secured in any desired position for the purpose of suitably aligning two rails or for changing the track from one gauge to another.

Having thus described my invention so that those skilled in the art may be enabled to practice the same, what I desire to secure by Letters Patent is defined in what is claimed, it being understood that the various details herein illustrated and described

are for the purposes of setting forth my invention and are not intended to define the scope of my invention.

What is claimed is:

1. A concrete tie having a cavity extending longitudinally thereof, and having a reinforcing metallic member disposed exteriorly of and enclosing the said cavity, and also having a rail securing insert embedded in the tie with its top surface substantially flush with the top surface of the tie, and securing means formed on the insert and embedded in the tie to securely hold the insert within the tie. 70

2. A concrete railway tie having a cavity extending longitudinally thereof for substantially its entire length, and having a wire netting in box-like form with closed ends about the said cavity, the said netting having depressions in the top surface thereof, and rail securing inserts embedded in the tie and projecting into the said depressions, the said inserts being substantially flush with the top surface of the tie. 80 85

3. A reinforced concrete railway tie having a cavity extending throughout substantially the entire length thereof and a rail securing member embedded in the tie, the top surface of the insert being substantially flush with the top of the tie, and securing means formed on the insert and embedded in the tie to securely hold the insert within the tie, said securing means including downwardly diverging walls formed on the base 100 of the insert. 105

4. A concrete tie having a cavity extending longitudinally thereof, and having a reinforcing metallic member disposed exteriorly of the said cavity and substantially enclosing the same, and also having a rail securing insert embedded in the tie with its top surface substantially flush with the top surface of the tie, and securing means formed on the insert and embedded in the tie to securely hold the insert within the tie, said securing means including downwardly diverging walls formed on the base of the insert. 110

5. The combination with a concrete railway tie of rail securing means, the said means comprising a rigid one-piece insert member having an interior recess and an opening therefrom through the top of the member, said member being embedded in the tie and having downwardly diverging walls formed on its lower portion to securely hold the member within the tie against movement, a clamping member cooperating with the said member to secure a rail against the member and tie, and means for securing the clamp and member in assembled position. 115 120

6. The combination with a concrete railway tie of rail securing means, the said means comprising a rigid one-piece insert member having an interior recess and an 125

opening therefrom through the top of the member, said member being embedded in the tie, and having downwardly diverging side walls extending into the tie material to 5 securely lock the member within the tie against movement, a clamping member co-operating with the said member to secure a rail against the member and tie, and means for securing the clamp and member in assembled position.

7. The combination of a concrete railway tie of rail securing means, said means comprising a rigid one-piece insert member embedded in the tie and extending longitudinally thereof and having a recess opening through the top thereof, said insert having longitudinally extending side walls, diverging downwardly and into the tie material to lock the insert therein, a clamping member 15 cooperating with the said insert to secure a rail against the insert and tie, and means for securing the clamp and insert in assembled position.

8. A concrete railway tie having a cavity 25 extending longitudinally thereof for substantially its entire length, and having a wire netting in box like form about the said cavity, the said netting having depressions in the top surface thereof, and rail securing inserts embedded in the tie and projecting into the said depressions, the said inserts being substantially flush with the top surface of the tie.

9. A concrete railway tie having a cavity 35 extending longitudinally thereof for substantially its entire length, and having a wire netting in box like form about the said cavity, the said netting have depressions in the top surface thereof, and rail securing inserts embedded in the tie and projecting into the said depressions, the said inserts being substantially flush with the top surface of the tie, and walls formed on the bases of the 40 said inserts, said walls diverging downwardly into the tie material for securely holding the inserts within the tie.

10. A concrete railway tie having a cavity 50 extending longitudinally thereof for substantially its entire length, and having a wire netting in box like form about the said cavity, the said netting having depressions in the top surface thereof, and rail securing inserts embedded in the tie and projecting into the said depressions, the said inserts 55 being substantially flush with the top surface of the tie, and walls formed on the bases of the said inserts and projecting

downwardly into the tie material for securely holding the inserts within the tie.

11. A concrete railway tie having a cavity 60 extending longitudinally thereof for substantially its entire length, and having a wire netting in box like form about the said cavity, the said netting having depressions in the top surface thereof, and rail 65 securing inserts embedded in the tie and projecting into the said depressions, the said inserts being substantially flush with the top surface of the tie, and means formed on the said inserts and projecting into the tie 70 material for securely holding the inserts within the tie.

12. A concrete railway tie having a cavity 75 extending longitudinally thereof for substantially its entire length, and having reinforcing means of box like formation about the said cavity, the said reinforcing means having depressions formed in the top surface thereof, and rail securing inserts embedded in the tie and projecting into the 80 said depressions, the said inserts being substantially flush with the top surface of the tie.

13. A concrete railway tie having a cavity 85 extending longitudinally thereof for substantially its entire length and having a wire netting in box like form with closed ends about the said cavity, the said netting having depressions in the top surface thereof and rail securing inserts embedded in 90 the tie and projecting into the said depressions, the said inserts being substantially flush with the top surface of the tie and means formed on the inserts and projecting into the tie material for securely holding the 95 inserts within the tie.

14. A concrete railway tie having a cavity 100 extending longitudinally thereof for substantially its entire length and having a wire netting in box like form with closed ends about the said cavity, the said netting having depressions in the top surface thereof and rail securing inserts embedded in the tie and projecting into the said depressions, the said inserts being substantially flush with the top surface of the tie and walls 105 formed on the bases of said inserts, said walls diverging downwardly into the tie material for securely holding the inserts with- 110 in the tie.

In testimony whereof I hereunto affix my signature this 15th day of October, 1924.

LOTHAR STOYE.
